UNITED STATES PATENT OFFICE.

SAMUEL C. HOEY, OF WILKINSBURG, PENNSYLVANIA, ASSIGNOR TO WESTINGHOUSE ELECTRIC & MANUFACTURING COMPANY, A CORPORATION OF PENNSYLVANIA.

ADJUSTABLE MOUNTING DEVICE.

Application filed January 3, 1920. Serial No. 349,285.

To all whom it may concern:

Be it known that I, SAMUEL C. HOEY, a citizen of the United States, and a resident of Wilkinsburg, in the county of Allegheny and State of Pennsylvania, have invented a new and useful Improvement in Adjustable Mounting Devices, of which the following is a specification.

My invention relates to an adjustable mounting device for slide rails and bed plates and it has particular relation to bed plates for motors and other machinery.

The object of my invention is to provide an efficient, durable, and economical means for adjustably mounting motors, dynamos and other machinery so as to permit the movement thereof for belt-tightening, proper alignment and other purposes.

Heretofore, motors have had a groove in each foot in which a corresponding tongue on the slide rail fitted, thereby permitting movement of the motor in a direction parallel with the groove.

In accordance with my invention, the motor foot and the bed plate are machined flat, and the guiding action is obtained by providing an elongated slot in the bed plate and by passing a holding member through this slot and through a hole in the motor foot.

A better understanding of my invention may be obtained by referring to the accompanying drawing in which Figure 1 is a top plan view of a motor supported by slide rails equipped with my invention; Fig. 2 is a transverse detail view, partially in section and partially in elevation of the same taken along the line II-II of Fig. 1, and Fig. 3 is a longitudinal detail view, partially in section and partially in elevation taken along the line III-III of Fig. 1, of the end of a guide rail, with a motor foot slidably mounted thereon. The other end of the guide rail is similar to the one shown in Fig. 3 except that the jack screw 8 is removed.

Referring particularly to Fig. 1, a motor 1, provided with feet 2, is mounted upon the slide rails or bent plates 3. Each slide rail has an elongated slot 4 in that portion which is in contact with the feet 2. A bolt 5 projects through the slot 4 of the slide rail 3 and a counter-bored hole 6 in the foot 2 and is retained in position by a nut 7. The bolt 5 may be moved along the slot 4 by rotating an adjusting screw 8.

Referring particularly to Figs. 2 and 3, the adjusting screw 8 is passed through a hole 9 in the end of the slide rail 3 and through a threaded head 10 of the bolt 5. Between the head 10 of the bolt 5 and the surface of the guide rail 3 is a connecting strap 11 which is a relatively long strip of metal having bent end portions 12 (only one end portion being shown). The bent end portions 12 prevent the bolts 5 from rotating while the nuts 7 are being screwed thereon. The strap 11 has two bolt holes 13 (one is not shown) spaced apart a distance equal to the distance between the bolt holes 6 in the corresponding feet 2 of the motor 1.

On each bolt 5 an annular locking ring 14 is mounted. This ring has two circular portions, one of which is of greater diameter than the other. The portion of the ring 14 that is of lesser diameter is seated in the slot 4 of the frame 3 and the remainder thereof fits in the counter-bored hole 6 of the motor foot 2. The bolt 5 has an annular groove 15 surrounding it in which a ring 16 of spring wire is retained.

The motor 1 has a pulley 17 to which is attached a driving belt. (Not shown.)

The method of assembling my slide-rail device is as follows:—a connecting strap 11 is so placed against the slotted portion of the slide rail 3 as to have the bent-end portions 12 turned outwardly. The bolts 5 are so positioned, through the bolt holes 13 of the strap 11 and the elongated slot 4 of the guide rail 3, that the adjusting screw 8 may be passed through the threaded portion of either bolt head 10. The annular ring 14 is next placed upon the bolt 5 in the manner shown in Figs. 2 and 3 of the drawing. The retaining ring 16 is positioned in the grooved portion 15 of the bolt 5, thereby holding the bolt in position until the motor foot 2 is mounted thereon and the nut 7 secured thereto. The adjusting screw 8 is inserted through the hole 9 in the frame 3 and the head 10 of the bolt 5.

When the screw 8 is so rotated that the bolt 5 is drawn toward the end of the guide rail 3, the connecting strap 11 and the motor 1 cause the remaining bolt 5 to move in the same direction. The movements of the bolts 5 also cause the motor feet 2 to be drawn in the same direction. If it is desired to reverse the movement of the motor, 110

it is necessary that the screws 8 be removed and inserted in the other ends of the guide rail 3 and the other bolts 5 (not shown).

The accurate machining of the motor feet 5 and bed plates which is required when the tongue-and-groove method of mounting machinery is employed, is rendered unnecessary by my invention, thereby lessening the cost and greatly reducing the risk 10 of rejection of either because of inaccurate workmanship.

The adjusting screw is on a direct line with the elongated slot and, when it is operated, the force exerted is parallel to the 15 direction in which the motor is moved.

The entire device is protected by being underneath the guide rail.

While I have shown a preferred form of my invention, it will be obvious to those 20 skilled in the art, that it is susceptible of various minor changes and alterations without departing from the spirit thereof, and I desire, therefore, that only such limitations shall be placed thereupon as are imposed by the prior art or as are specifically 25 set forth in the appended claims.

I claim as my invention:—

1. In an adjusting-screw device, the combination with a frame member having an 30 elongated slot, of a bolt slidably mounted in said slot and having a transversely threaded portion in its head, means for ensuring a sliding fit of said bolt in said slot, and screw means co-operating with said threaded head, adapted to alter the position of said bolt in the slotted portion of said frame.

2. In a bed-plate device, the combination with a frame member having an elongated slot, of a bolt slidably mounted in said slot, 40 having a transversely threaded portion in its head and an annular groove above the plane of the body portion of said frame member, an annular member positioned by and below said annular groove and adapted 45 to secure a sliding fit of said bolt in said slot, and an adjusting screw mounted in said frame and registering in said transversely threaded portion of said bolt head and adapted to actuate said bolt throughout the 50 length of said slot.

3. In an adjusting-screw device, the combination with a frame member having an elongated slot, of a bolt slidably mounted in said slot and provided with a transversely 55 threaded portion in its head, annular means mounted on said bolt and seated in said slot, adapted to secure a sliding fit of said bolt in said slot, and a threaded member mounted in said frame, engaging and registering 60 in the transversely threaded portion of the head of said bolt, adapted to alter the position of said bolt throughout said slot.

4. In an adjusting screw device, the combination with a frame member having an elongated slot, of a bolt slidably mounted in 65

said slot and provided with a threaded end portion, an annular member so mounted upon the said bolt that it is partially between the said bolt and the sides of the said slot, thereby insuring a sliding fit of said bolt, and a threaded member mounted in the said frame and engaging the said bolt for altering the said bolt's position throughout the length of the said slot. 70

5. In an adjusting screw device, the combination with a frame member having an elongated slot, of a bolt slidably mounted in the said slot and provided with a threaded end portion and an annular groove, an annular member so mounted upon the said bolt that it is partially between the said bolt and the sides of the said slot, a circular spring positioned in said groove surrounding the said bolt and a threaded member mounted in the said frame and engaging the said bolt for altering the said bolt's position throughout the length of the said slot. 75 80 85

6. In a bed-plate device, the combination with a frame member having an elongated slot, of bolts slidably mounted in said slot 90 and each having a transversely threaded portion in its head, a strap attached to said bolts adapted to position them a predetermined distance apart and cause them to coact, and screw means co-operating with and 95 engaging the threaded head of one of said bolts, adapted to actuate and alter the position of said bolts throughout the length of said slot.

7. In a bed-plate device, the combination with a frame member having an elongated slot, of bolts slidably mounted in said slots and each having a transversely threaded portion in its head, a strap attached to said bolts adapted to position them a predetermined distance apart and cause them to coact, and screw means co-operating with and substantially in alignment with the threaded head portion of said bolts, adapted to actuate and alter the position of said bolts throughout the length of said slot. 100 105 110

8. In an adjusting-screw device, the combination with a frame member having an elongated slot, of bolts slidably mounted in the said slot and each having a threaded end portion and an annular groove, a strap connecting the said bolts for positioning them and causing them to co-act, annular members so mounted upon each of the said bolts that they are partially between the 115 bolts and the sides of the said slot, circular springs positioned in said grooves surrounding the said bolts, and an adjusting screw mounted in the said frame and engaging one of the said bolts for altering the said bolts' 120 positions throughout the length of the said slot. 125

9. In a bed-plate device, the combination with a frame member having an elongated slot, of a bolt slidably mounted in said slot 130

having a transversely threaded portion in its head, an annular groove in said bolt above the plane of the body portion of said frame member, an annular stop member 5 registering in said groove, an annular member mounted on said bolt, seated in said slot and locked in position by said groove and stop member, adapted to ensure a retention and sliding fit of said bolt in said slot, and an adjusting screw mounted in said frame and registering in said threaded portion of said bolt head, adapted to actuate said bolt throughout the length of said slot.

In testimony whereof, I have hereunto subscribed my name this 8th day of December, 1919.

SAMUEL C. HOEY.
